UNITED STATES PATENT OFFICE.

CHARLES A. TUCKER, OF ISLIP, N. Y., ASSIGNOR TO CHARLES R. HEDDEN,
OF NEWARK, N. J., AND TUCKER & BAXTER, OF BROOKLYN, N. Y.

APPLIANCE FOR CLOSING OPENINGS IN BUILDINGS AUTOMATICALLY.

SPECIFICATION forming part of Letters Patent No. 350,451, dated October 5, 1886.

Application filed January 28, 1886. Serial No. 190,071. (No model.)

To all whom it may concern:

Be it known that I, CHARLES A. TUCKER, a citizen of the United States, residing in the town of Islip, in the county of Suffolk and State of New York, have invented certain new and useful Improvements in Appliances for Closing Openings in Buildings Automatically by Electricity; and I do hereby declare that the following is a full, clear, and exact description thereof, reference being had to the accompanying drawings, which form part of this specification.

My invention is especially applicable to warehouses and storage-buildings in which doors and windows and other ventilating-openings are required to be left free for the purpose of ventilation, and where it is important to close the same quickly in case of fire, in order to prevent draft and confine the flame, &c., but of course it may be employed in any other structure for analogous purposes; and it consists, essentially, of an arrangement of the doors, shutters, or other closing devices, so that these will operate to close their appropriate openings automatically at the proper time.

Figure 1 is an elevation of the inner wall of a room, showing my invention as applied to a sliding door arranged on the face of the wall. Fig. 2 is an elevation of a portion of a wall, showing my invention as applied to a sliding door arranged within the wall. Fig. 3 is a section of Fig. 2 on the line of the upper face of the arm D. Figs. 4, 5, and 6 are details of the detent e. Fig. 7 is an elevation of part of a hinged shutter and window, showing another method of applying my invention. Fig. 8 is a section on the plane of the window-casing in Fig. 7. Fig. 9 shows a releasing device which may be employed within the building with the device in Fig. 8. Fig. 10 shows a releasing apparatus in elevation, which may be employed on the outer wall of buildings. Fig. 11 is an end view of the catch w in Fig. 10. Fig. 12 is an outline of an electric circuit that may be arranged for operating my invention.

Similar letters of reference indicate like parts in all the drawings.

C represents the wall of the room, and B the doorway or other opening therein, and A the door for closing the same. In Fig. 1 this

door A is shown arranged to move on an incline, b, which is attached to the face of the wall, the door being suspended thereon by suitable hangers, a a, so that if left free to move the door A would run down the incline by gravity and close the opening B.

On the door A a detent, e, is secured, which consists of a friction-roller, j, in suitable bearings therefor. (Shown enlarged in Figs. 4 to 6.)

At a suitable point on the wall a lever, D, is pivoted, as at k, having an up-and-down motion, and provided at its free end with a catch, i, so that it will engage with the detent c and retain the door in position open, and on being raised will be disengaged from the detent and allow the door to move down the incline and close the opening.

To regulate the scope of motion of the catch i, a set-screw, h, is arranged beneath the lever D, and by sloping the face of the catch i opposite to the face that engages with the detent c the catch is automatically pushed up as the detent strikes against it when the door is pushed back.

At a suitable point on the lever D an armature, d', is secured, and above that, on the wall, a magnet, d, is attached in such relative position that when the magnet is excited it will attract the armature d' and draw it and the catch i up, so that the catch will release the detent c and permit the door to pass down to the opening B. The magnet d is electrically connected to a suitable battery, as f, and to a thermostat, e, by wires g g. The thermostat should be disposed at a suitable place near the ceiling of the room, where it will be most quickly affected by the heat, and should be set at such a degree as will operate the device as soon as the heat of a fire operates upon the thermostat. The parts are to be arranged so that until the desired degree of heat is reached the electric circuit will be broken, but will be closed when the temperature rises.

A convenient and sensitive thermostat consists of a thermometer having a wire fused in its bulb to reach the mercury, and another wire fused into its stem at the designed degree of heat, these wires being then connected to the positive and negative poles of the battery, with the magnet d intermediate. When the

mercury rises to the designated degree of heat, it comes into contact with the wire fused into the stem at that point and closes the circuit. Any other thermostat of sufficient sensitivity, however, will answer the purpose.

In Figs. 4 to 6 I show the details of the detent *c* for raising and engaging with the catch *i*. It consists of a base, *j*, through which it is secured to the door, and uprights *j' j'*, in which 10 the detent-roller *j* is pivoted. The faces of these uprights toward the catch *i* are inclined, as shown clearly in Fig. 4, and the periphery of the roller *j* is carried beyond the line of the uprights *j'*, so that the face of the catch *i*, when 15 the door is held open, will bear against the roller only. By this arrangement the lever *D* can be operated with very little power, as but little friction is encountered in raising it.

The operation is as follows: When the door 20 is opened, the roller *j* of the detent *c* strikes against the sloping face of the catch *i* and raises it until the detent has passed within the catch, which then drops down by its own weight and engages with the detent, holding 25 the door in place, open, the electrical circuit being broken. When the temperature rises far enough to operate the thermostat and close the electrical circuit, the magnet *d* becomes 30 excited, attracts the armature *d'*, and thereby raises the lever *D*, and with it the catch *i*, disengaging it from the detent, when the door at once slides down the incline and closes the opening *B*.

In Figs. 2 and 3 a modification of the device 35 is shown. In this the door *A* is within the wall *C*, instead of on the side of the wall, as in Fig. 1. In this arrangement I bend the end *c'* of the lever *c* and carry it through a suitable opening in the wall to engage with the detent *c* at the desired point; otherwise the 40 operation and structure are the same as those already described.

In Figs. 7 to 11 I show my invention as applied to shutters, which may be hinged in the usual manner to close the windows. *E* is the 45 opening or window, and *F* the shutter for closing it. On the shutter at a suitable point I arrange a spring-bolt, *l*, disposed so that when left free it will engage in the staple *m* 50 on the side of the building. Back of the bolt an eye, *n*, is arranged on the shutter *F*, which acts as a guide for the chain or cord *o*, which is secured to the end of the bolt *l* and carried through a slot in a swinging arm, *p*, and 55 around the pulleys *q q*, which are pivoted to the under side of the window-casing *G*, and over the pulley *r*, pivoted to the inner face of the wall *H*. To the end of the cord or chain *o* a weight, *I*, is attached, sufficient to 60 close the shutter when left free to draw on the same. On the wall, near the pulley *r*, a support, *J*, is pivoted, as at *s*. In this is eccentrically pivoted a wheel, *s*, in such position that it will bear against the chain or cord *o* 65 where it passes over the pulley *r*, and prevent the weight *I* drawing on the cord *o*. The face of the wheel *s* may be suitably roughened or

notched to catch and clog the cord *o*. Near the support *J* a suitable bearing, *v*, is arranged, which may be a pin with a friction-roller, and between this bearing and the pivoted support *J* a plug, *u*, is suspended which holds the support *J* steadily in such position that the wheel *s* will clog the rope *o*. This plug *u* is pivotally attached to a pivoted lever, *K*, 70 provided with an armature, *d*. Under this is placed a magnet, *d*, which is connected by the wires *g g* with the positive and negative poles of a suitable battery, having a thermostat intermediate, as in the other instance of my invention already described. A spring, *s'*, is attached to the support *J* and to the wall in such relation that when the plug *u* is withdrawn this spring will draw in the support *J* and carry the clog-wheel *s* away from the 75 pulley *r*. The arm *p* is pivoted to the under side of the window-casing in such position that when carried in parallel to the side of the casing *G* it will not project beyond it, and the rope *o* is thickened up in a suitable manner at *o'*, so that that point cannot pass through the slot in the arm *p*, but not so much as to prevent easy passage across the pulleys *q q r*.

The operation is as follows: The weight *I* is 80 drawn up so as to slacken the rope between the pulley *r* and the spring-bolt *l*, in order to allow the latter to operate on throwing open the shutter. As the weight draws on the rope, the eccentric *s* bears against the rope and clogs 85 it. The shutter in being opened draws with it the arm *p*, which is moved by the thick portion *o'* of the rope, and the bolt *l* is shot into the staple *m*. When the thermostat closes the circuit and excites the magnet *d*, the armature *d'* is attracted, drawing down that end of the lever *K* pulling up the plug *u*. This allows the spring *s'* to draw back the support *J* and carry the eccentric *s* away from the chain or 90 cord *o*, allowing the weight to draw upon the cord, thereby drawing back the bolt *l*, and then drawing in the shutter *F*.

In Fig. 10 a catch is shown which may be 95 arranged on the outer wall of a building. In this *w* is a catch, which is suitably pivoted, so that it will tend to swing up and hold the shutter *M*. It has an inclined face, so that when the shutter strikes it the engaging portion of the catch will be pressed down until the edge of the shutter has passed over it, and then its 100 weighted end will bear down, raising up the engaging end, as shown in Fig. 11. A friction-roller operating on its engaging-face may be employed to diminish the friction. On the face of the wall a suitable box or case, *N*, 105 contains the magnet *d*, and a pivoted lever and an armature, *L*. The magnet *d* is connected with a battery and thermostat, as already described, by the wires *g*. In this arrangement the cord *o*, arm *p*, pulleys *q q*, pulley *r*, and weight *I* are also employed; but the cord *o* is fastened to the eye *n* and the weight is left free to draw on the shutter. When the magnet *d* is excited, it attracts the armature, draw- 110 115 120 125 130

ing down the armature end of the lever, bringing up the other end of that lever, and throwing up the weighted end of the catch *w*, which allows the weight *I* to draw on the cord *o* and close in the shutter. Only one shutter is shown 5 in the drawings; but of course the invention can be applied to as many shutters or doors as may be desired.

In Fig. 12 I show in outline a circuit for operating my invention arranged in a system. *P P* are the floors of a building. *d d* are the magnets. *f* is the battery, and *e e* are the thermometers or thermostats. One pole of the battery *f* is connected through all the magnets 15 to all the bulbs of the thermometers. The other pole of the battery *f* is connected by the wire *g* to the stems of all the thermometers. By this arrangement when any or all of the thermostats become heated and close the circuit, 20 all the magnets become excited and operate upon all the closing devices in the system, closing every opening in the warehouse or building which is provided with my invention.

Having thus described my invention, what 25 I claim as new, and desire to secure by Letters Patent, is—

1. The appliances shown for closing openings in buildings by electricity, consisting of suitable closing-doors, adapted to close their 30 openings automatically when free, a suitable detent, as *e*, and catch *i*, to retain the same in position open, in combination with an armature, *d'*, magnet *d*, battery *f* and its connections, to form an electrical circuit, and a thermostat, as *e*, interposed in said circuit and adapted 35 to close the same at a determined degree of temperature, substantially as described and shown.

2. In appliances for closing openings in 40 buildings by electricity, a closing-door adapted to move across its opening automatically when free, having a detaining device, a suitable catch to engage with such detaining device and retain the door in position open, and an armature adapted to actuate the catch and with- 45

draw the same, in combination with suitable magnets to operate such armature, the magnets arranged in an electrical circuit adapted to be closed by a suitable thermostat, substantially as described.

3. In appliances for closing openings in 50 buildings by electricity, the combination of the detent *e*, provided with friction-rollers *j*, pivoted catch-bar *D*, and adjusting screw *h*, substantially as described.

4. In appliances for closing openings in 55 buildings by electricity, the combination of the door *F*, swinging arm *p*, cord *o*, bolt *l*, staple *m*, pulleys *q q r*, weight *I*, and a suitable catch to support the weight in position, with a releasing mechanism operated by an 60 electromagnet and adapted to release the weight to draw the door *F* across its opening, substantially as described and shown.

5. In appliances for closing openings in 65 buildings by electricity, a series of closing-doors adapted to move across their openings automatically when free, such doors provided with suitable detents and catches to engage with such detents and hold the doors open, 70 and armatures to actuate the catches and release the closing-doors, in combination with a series of magnets arranged to attract such armatures, electrically connected with each other and with the poles of a battery, and a 75 series of thermostats adjusted to close the circuit at determined degrees of temperature, and electrically connected with each other and with the other pole of the battery and with the magnet-wires, and adapted to complete the 80 circuit and excite all the magnets in the series when the circuit is closed by any one of such thermostats, substantially as described and shown.

CHARLES A. TUCKER.
